UNITED STATES PATENT OFFICE.

HARRY F. SMITH, OF DAYTON, OHIO, ASSIGNOR, BY MESNE ASSIGNMENTS, TO THE GAS RESEARCH COMPANY, OF DAYTON, OHIO, A CORPORATION OF OHIO.

METHOD OF PREVENTING WALL ACTION.

1,417,636.

Specification of Letters Patent. Patented May 30, 1922.

Application filed May 24, 1918. Serial No. 236,263.

To all whom it may concern:

Be it known that I, HARRY F. SMITH, a citizen of the United States of America, residing at Dayton, county of Montgomery, 5 and State of Ohio, have invented certain new and useful Improvements in Methods of Preventing Wall Action, of which the following is a full, clear, and exact description.

10 This invention relates to gas producers and more particularly to the prevention of "wall action" therein.

In the operation of gas producers there is a decided tendency for a portion of the 15 air blast to pass upwardly along the lining of the generating chamber and through adjacent layers of the fuel bed more freely than through the body of the fuel bed. There is also a tendency for the fuel bed 20 to shrink away from the lining of the producer as the volatile components of the fuel are driven off, which permits of an even more ready flow of air blast adjacent the lining. Where such freer flow of air blast 25 occurs the rate of combustion will be greater than the rate of combustion in the body of the fuel bed. This gives rise to channels or chimneys in the fuel bed which permit the flow of considerable quantities of air 30 blast therethrough without such air coming into intimate contact with the incandescent fuel. As a result, some part of the air blast will pass through the fuel bed without combining with the carbonaceous 35 material thereof. Such portion of unacted upon air blast will either unite with the combustible gas in the upper part of the generating chamber to form carbon dioxide or will pass unchanged into the delivery

40 main where it will act as a diluent to cut down the heat value of the gas. This condition is known as wall action.

Wall action is especially troublesome in 45 gas producers of large size where, because of the considerable grate area, it is more difficult to secure uniform distribution of the air blast and uniform consistency in the fuel bed. The object of the present invention is to prevent this wall action by 50 causing the air blast to pass through the body of the fuel bed, while at the same time keeping the temperature of the layer of fuel immediately adjacent the lining comparatively low, thus preventing the 55 burning of channels or chimneys therein

even though some part of the air blast should pass upwardly through this particular layer of fuel.

In carrying this invention into effect, an inert, or relatively inactive, gas is introduced into the generator in such wise as to 60 form a layer or blanket of gas coextensive with that part of the lining of the generating chamber which is adjacent the fuel bed. By forming such a blanket of inert, or inactive, gas or vapor the air blast is deflected toward the center of the fuel bed 65 which of itself will prevent the formation of channels or chimneys adjacent the outer edges thereof. Further, the presence of this inert, or inactive, blanket will tend to keep the temperature of that particular portion of the fuel bed in which it exists, comparatively low, so that the development of excessive temperatures, which are present 70 where such channels or chimneys are burned in the fuel bed, are prevented.

In the drawing in which like characters of reference designate like parts throughout the several views thereof,

Fig. 1 is a sectional view, along the line 1—1 of Fig. 2, through a producer illustrating an embodiment of a preferred form of apparatus for carrying this invention into effect;

Fig. 2 is a sectional view through the apparatus illustrated in Fig. 1, along the line 2—2 thereof;

Fig. 3 is a sectional view, along the line 3—3 of Fig. 4, of a modified form of apparatus for carrying this invention into effect; and

Fig. 4 is a sectional view, along line 4—4 of the apparatus illustrated in Fig. 3.

In the drawing, 1 designates the shell of 95 a producer which may be of any conventional design. Inside of shell 1 is a lining 2 of fire brick or similar material. Located near the bottom of the producer is a grate 3 for supporting the fuel bed, and carried at the top of the producer is a fuel feeding device 4. Opening into the producer adjacent the bottom thereof is an air inlet port 5, so positioned that the air or other gas introduced therethrough will enter the 100 interior of the producer below the grate, pass upwardly through the grate and fuel bed supported thereby, and then outwardly through the offtake main 6. It is the general producer practice to introduce a mix- 105 110

ture of air and moisture into the generating chamber for reaction with the fuel bed therein to produce a combustible gas. The term "air blast" is used herein to designate generally this mixture of air and moisture, whether that blast be introduced under pressure or under suction. The producer thus described is of a conventional, suction-operating type.

- 10 Near the bottom of the producer lining is a zone of metallic brick 7. As illustrated, this zone of metallic brick consists of hollow brick so formed that, when laid in position, the hollow spaces therein form a continuous 15 manifold 8 extending completely around the producer as clearly illustrated in Fig. 2. Leading through the wall of the producer and opening into this manifold 8 are a plurality of pipes 9 adapted to admit steam, exhaust gases, gas from the main 6, or any other desired gas or vapor which is inert, or relatively inactive, under the conditions which obtain within the fuel bed. Leading through the zone of metallic brick 7 are a 20 large number of passages 10 connecting the interior of the manifold 8 with the interior of the generating chamber of the producer. With this structure it is obvious that if steam or other relatively inert, or inactive 25 gas or vapor, is introduced into the manifold 8 through the pipes 9 under a pressure preponderating slightly over the pressure existing in the generating chamber, such gas or vapor will pass through the numerous 30 passages 10, will be deflected and carried upwardly by the current of ascending gases within the chamber, and will tend to form a blanket along the lining of the generating chamber which will prevent too ready upward 35 passage of the air blast through the fuel bed immediately adjacent the said lining. In addition, any tendency toward unduly rapid combustion of the fuel adjacent the lining will be prevented by the relatively inactive gas or vapor. And this of 40 itself will effectively prevent the formation of chimneys or channels, since these can be formed only where the rate of combustion is comparatively too rapid.
- 45 It is obvious that hollow brick made of some material other than metal may be substituted for the metal brick 7. It is also obvious that the manifold 8 need not necessarily be located within the producer shell. It is quite feasible to entirely dispense with 50 the zone of metallic brick 7 and simply provide a steam manifold extending completely around the outside of the producer shell and connected with the interior of the generating chamber by means of a plurality of pipes whose inner ends terminate adjacent the inner surface of the producer lining.

In Fig. 3 is illustrated a different form of apparatus for carrying this method into effect. In the apparatus illustrated therein

the producer, grate, air inlet port, gas off-take port and fuel feeding device are the same as illustrated in Fig. 1. The major part of the fire brick lining 2 is also similar to that shown in Fig. 1. In this modification, however, I have inserted two layers of fire brick, composed of the same material as the rest of the lining, but so arranged that when in place there will be two vertical passages 11 extending downwardly along the producer shell to the zone of metallic brick 12. The metallic brick 12 are similar in structure to the brick 7 of Fig. 1, in that they have, when in place, the same manifold 8 running therethrough and the same 75 passages 10. Several of the brick constituting this zone, however, have an additional passage-way 13 adapted, when the brick are laid in position, to register with the passages 11 and connect those passages with the manifold 8.

80 Connecting the top of the passages 11 with the interior of the generating chamber are two radial passages 14. Passing through the top of the producer shell and into the 85 passages 11 are two steam pipes 15, the inner ends of which carry steam nozzles 16 which terminate adjacent the passages 14, the arrangement being such that the nozzles 16, passages 14, and passages 11 constitute in effect ejectors for drawing gas from the generating chamber and forcing such gas along the passages 11 into the manifold 8, and then through the passages 10 back into the 90 interior of the generating chamber. Located 95 in each of the pipes 15 is a control valve 17, by means of which the ejector action may be readily controlled. It is obvious that when steam at the desired pressure is introduced through the nozzles 16, gas from the top of the generating chamber will be forced downwardly through the passages 11 and, mixed with the steam coming from the nozzles, will pass through the passages 10 into the 100 interior of the generating chamber wherein the mixed gas and vapor will spread out along the lining of the producer to form a deadening blanket, in the same manner as described in connection with Fig. 1.

105 A number of different kinds of gas or vapor may be used advantageously in carrying this invention into effect. I have found from experiment, however, that steam when used alone, seems to give the most satisfactory results. Not only does steam form a 110 blanket along the lining of the producer which deflects the air blast toward the interior of the generating chamber where it passes through the body of the fuel bed, but it has a quenching action which lowers the 115 temperature of the fuel bed adjacent the lining, so that undue consumption of the fuel in this zone is obviated and the formation of the channels is thereby effectively prevented.

It is evident that any other gas or vapor tending to prevent undue combustion of those portions of the fuel bed covered by it will have practically this same effect. This 5 would be true in the case of engine exhaust gases in which the presence of large quantities of carbon dioxide would tend to make the development of excessive temperatures impossible. It has also been found that a 10 mixture of producer gas and steam, such as could be fed into the generating chamber in the type of apparatus illustrated in Fig. 3 has about this same effect, since the producer gas itself is not capable of sustaining 15 combustion in the fuel bed, although it can of course burn in the presence of atmospheric air, and in addition, the steam carried therein tends to exercise a quenching action as described above.

20 While the methods herein described, and the forms of apparatus for carrying those methods into effect, constitute preferred embodiments of the invention, it is to be understood that the invention is not limited to 25 these precise methods and forms of apparatus, and that changes may be made in either without departing from the scope of the invention which is defined in the appended claims.

30 What I claim as new and desire to secure by Letters Patent is:

1. The method of generating producer gas, in which a fuel bed of ignited carbonaceous material is maintained within the generating 35 chamber of the producer, which consists in blasting the body portion of the fuel bed within the generator with a fluid adapted to react with the fuel to form a combustible gas, and at the same time passing through 40 the zone of fuel adjacent the wall of the generator sufficient of a fluid which is relatively inactive with respect to the fuel to exclude from such zone substantially all of the relatively active fluid which is being 45 passed through the body of the fuel bed.
2. The method of generating gas in a gas producer which consists in maintaining a fuel bed of carbonaceous material within the

producer; passing a mixture of air and steam through the body of such fuel bed, to 50 generate a combustible gas; and at the same time maintaining a blanket of a fluid incapable of sustaining combustion within the zone of the fuel bed adjacent the wall of the producer to substantially prevent the 55 combustion of the fuel within said zone.

3. The method of generating gas in a gas producer which consists in maintaining a fuel bed of carbonaceous material within the producer; passing through the body portion 60 of the fuel bed a fluid which is capable of sustaining combustion of the fuel, to cause the generation of combustible gas; and at the same time passing through the zone of fuel adjacent the wall of the producer a fluid 65 which is incapable of sustaining combustion of the fuel.

4. The method of generating gas in a gas producer which consists in maintaining a fuel bed of carbonaceous material within the 70 producer; passing through the body portion of the fuel bed a fluid which is adapted to sustain combustion of the fuel, to cause the generation of combustible gas within said bed; and at the same time maintaining 75 within the zone of fuel adjacent the wall of the producer a blanket of fluid which is incapable of sustaining combustion of the fuel in the fuel bed; the said blanket being such as to deflect towards the center of the fuel 80 bed the fluid adapted to sustain combustion therein.

5. The method of preventing wall action in a gas producer which consists in withdrawing a portion of the gas from above the 85 fuel bed, mixing it with a non-combustible fluid, and introducing the mixture into the fuel bed in such wise as to form a blanket of the mixed gas and non-combustible fluid within the zone of fuel adjacent the walls of 90 said producer.

In testimony whereof I affix my signature.
HARRY F. SMITH.
